UNITED STATES PATENT OFFICE.

GEORGE C. MARTIN, OF LOS ANGELES, CALIFORNIA, ASSIGNOR TO JOHN M. CARSON, OF LOS ANGELES, CALIFORNIA.

AUTOMATIC SIGNAL DEVICE.

1,215,042.

Specification of Letters Patent.

Patented Feb. 6, 1917.

Application filed April 2, 1913. Serial No. 758,294.

To all whom it may concern:

Be it known that I, GEORGE C. MARTIN, a citizen of the United States, residing at Los Angeles, in the county of Los Angeles and State of California, have invented certain new and useful Improvements in Automatic Signal Devices, of which the following is a specification.

This invention relates to improvements in signaling devices, and particularly to electrically operated warning signals especially useful in connection with railway crossings and the like.

It is an object of the invention to provide a simple yet especially reliable signaling mechanism which may be used for railway purposes, and particularly for railway crossings where there is danger and where a moving as well as a sounding device is needed to attract the attention of the eyes as well as of the ears of people in the neighborhood of the signal.

It is also an object of the invention to provide a signaling device in which a rocking target may be oscillated by means of a suitable motor preferably of the electric type, the structure being such that the motor may be removed from position and another set into its place for operating the target while the disabled motor is repaired.

It is also an object of the invention to provide a signaling device in which a rock shaft is actuated by suitable mechanism, the rock shaft operating a target and being also provided with an actuating member adapted to operate a gong mechanism at each oscillation of the target.

In the accompanying drawings, forming part of this specification,

Figure 1 is a vertical, sectional view taken through the casing of a signaling device constructed in accordance with the present invention, the section being taken to one side of the mechanism in said casing.

Fig. 2 is a horizontal, sectional view through the casing of the signaling device, the mechanism within the same being shown in top plan.

Fig. 3 is a vertical, sectional view taken upon the line 3—3 of Fig. 2.

Fig. 4 is a detail view in side elevation of the target carrying arm and the target, the shaft carrying the target arm and portions of the target arm being shown in section.

Fig. 5 is a detail, sectional view upon an

enlarged scale, taken through the central portion of the target and the light mechanism mounted therein.

Fig. 6 is a fragmentary detail sectional view showing the gong operating mechanism and the rocking member controlling the same.

The details and features of the invention will now be more specifically described, reference being had to the drawing, in which 5 indicates a casing or box adapted to contain the actuating mechanism of the signaling device, the said box being so constructed that it may be readily mounted upon a post, arm or other desired support in any suitable manner. Within the casing 5 is journaled a rock shaft 6 mounted in suitable bearings 7 carried by the base of the casing 5. The said rock shaft is preferably hollow, and may be made of ordinary piping, the ends thereof being allowed to project through openings in the sides of the casing 5. One end of the rock shaft is connected by a T-coupling 8, with an upwardly extending hollow arm 9 which carries a target 10 at its upper end. The said arm 9 may also be made of ordinary piping screwed at its lower end into the coupling 8. The upper end of the arm 9 is preferably slotted for a sufficient distance to receive the lower edge of the target 10. The flange of the target is inserted in said slot as shown in Figs. 1 and 4, and rivets or bolts 11 are employed to secure it firmly in place. The central portion of the target 10 is apertured and circular casings 12 having peripheral flanges 13 are secured so as to cover said aperture and form an inclosing space in the middle of the target for the reception of a lamp 14. The casings 12 are provided with annular ribs or shoulders 15 against which lenses 16 are placed, and split rings 17 are sprung into place against the lenses and behind overhanging flanges 18 on the said casings for removably holding the lenses in place. By this structure, either one of the lenses may be readily removed at any time for gaining access to the lamp or for cleaning the lenses. The lamp 14 is preferably an electric lamp and conductors 19 and 20 pass through the hollow arm 9 to supply the said lamp with a suitable current of electricity. The lower end of the T-coupling 8 also carries a lamp as 21, and the end of the rock shaft 6 upon

80

110

the other side of the casing 5 is usually provided with a lamp 22, an elbow 23 being provided upon the end of the shaft 6 to hold said lamp. The conductors extend through 5 the hollow arm 9, the hollow shaft 6 and the hollow coupling 8, as well as the elbow 23 so as to connect all of the said lamps in series. The conductors 19 and 20 are led from the hollow shaft 6 through an opening 24 formed therein, and thence to any 10 suitable source of electrical energy.

The shaft 6 is preferably oscillated at a moderate speed to throw the target 10 back and forth, thus attracting the eyes of all 15 passers. The oscillation is preferably accomplished through the agency of suitable gearing and interconnecting means, the gearing being adapted to receive its actuation from a pinion 25 secured to the shaft of an 20 electric motor 26. The electric motor is removably mounted upon a boss 27 formed on the base plate of the casing 5, so that the said motor can be readily set in place or removed for repair when required and another 25 motor may be substituted therefor, without interfering with the other mechanism of the device.

The pinion 25 meshes with a gear wheel 28 which is carried by a shaft 29 journaled 30 upon standards 30 and 31 within the casing 5. The said gear 28 carries a pinion 32 upon one of its faces which meshes with a gear wheel 33 secured to a countershaft 34 arranged adjacent to the shaft 29. The said 35 countershaft 34 is journaled upon standards 35 and 36 in the casing 5 and one end of said shaft 34 is provided with a crank arm 37 which is connected by means of a link 38 with an arm 40 secured to the rock shaft 40. The arm 40 is made longer than the crank arm 37 so that the said arm 40 will only be oscillated though the crank arm turns entirely about its axis. It will be readily understood that when the motor 26 is actuated, that its pinion will drive the train 45 of gearing just described and cause the oscillation of the shaft 6, and the target arm 9 as well, as the motor is kept running.

The sounding or gong mechanism employed is operated in conjunction with the target and to accomplish this purpose, a sector 41 is rigidly secured to the shaft 6 and provided near its outer periphery with the gear teeth 42 which mesh with the teeth of 55 a beveled gear 43 secured to a vertical shaft 44. The vertical shaft 44 is mounted at its lower end in a bearing 45 carried by the cap of the journal 7 while the upper end of the shaft 44 finds a bearing in the cover of the 60 casing 5. The shaft 44 extends above the cover and is provided with a tapper arm 46 arranged within a gong 47. The tapper arm 46 is provided with an enlarged end portion forming a tapper 48 adapted to 65 strike the gong upon each oscillation of the

shaft 44. It will be readily understood that as the sector 41 is oscillated by the rocking of the shaft 6, that the shaft 44 will be turned back and forth so that the gong or bell will be struck by the tapper at each extreme of its movement.

It will be understood that the mounting of the various shafts in the mechanism may be altered in detail without departing from the spirit of the invention. The provision 75 of the rock shaft with a target carrying arm and a gong operating arm or sector makes it possible to always secure both a sight and sound signal, and the manner of mounting the actuating motor so as to rock said shaft 80 6 is important since the motor can be so readily removed for repair and replaced by another during the time required for such repair. The gong operating mechanism is so constructed that a positive sounding 85 of the gong is secured every time the target is swung in either direction.

The construction of the target carrying arm 9 is also important since a very strong mounting of the target is secured, yet with 90 a simple and easily constructed arrangement of the parts. The lamp in the target can also be reached without disconnecting any of the parts of the target device, or without taking the target from the said arm 9. It will be 95 readily understood that the above mechanism may be set at any point of danger or at railway crossings, and its motor be so connected with track operating means that the signal may be set in operation upon the 100 approach of a car or train, and caused to stop again after the point of danger has been passed by the said car or train.

What is claimed is:

1. An electric signaling device comprising 105 a base, a hollow rock shaft journaled upon said base and projecting at its ends beyond the same, a hollow signal carrying arm projecting from one end of said shaft, signal lamps projecting in the other direction from said shaft one at each end, an arm projecting from said rock shaft, a crank connected with said arm but of less length than the arm whereby continuous turning of the crank will operate to oscillate the said arm 110 and the signal devices projecting from said shaft, gearing for turning the said crank and an electric motor for driving the said 115 gearing and continuous wiring extending from a source of electrical energy through 120 the hollow rock shaft and hollow oscillating arm to the said signals.

2. An electric signaling device comprising 125 a base plate, a rock shaft journaled thereon and carrying oppositely extending oscillating signals, means for rocking said shaft and oscillating said signals, a shaft extending at right angles to said rock shaft, a gear thereon, a gear on said rock shaft meshing therewith for communicating move- 130

ment directly from the rock shaft to the other shaft and a gong device operated by said latter shaft whereby the gong striker and signals are moved simultaneously.

5. 3. An electric signaling device comprising a base plate, a rock shaft mounted thereon and having signals at its ends, an actuating arm secured to the said shaft, a rock shaft extending at right angles to the rock shaft 10 and having a gong sounding hammer thereon, a gear on said shaft, a segmental gear secured to the rock shaft and meshing with said gear whereby the gong will be sounded when the rock shaft is operated for moving 15 the signals, a gong and electrical mechanism for rocking said shaft.

4. A signaling device comprising a housing, a rock shaft mounted therein and car-

rying a vibrating signal arm, arms projecting from said rock shaft, actuating means 20 mounted in the housing and connected with one of said arms for rocking said rock shaft, a sounding device mounted on said housing, a tapper for engaging said sounding device, a rock shaft carrying said tapper, a gear 25 for turning said shaft and a gear segment intermeshing with said latter gear and carried by the other arm upon said rock shaft whereby the tapper will be actuated when the warning signal is vibrated.

In testimony whereof, I have hereunto set my hand, in presence of two witnesses.

GEO. C. MARTIN.
